UNITED STATES PATENT OFFICE.

PHILLIP EBELING, OF MOUNDSVILLE, WEST VIRGINIA, ASSIGNOR TO FOSTORIA GLASS COMPANY, OF MOUNDSVILLE, WEST VIRGINIA, A CORPORATION OF WEST VIRGINIA.

DESIGN FOR A GLASS DISH OR SIMILAR ARTICLE.

48,245.

Specification for Design.

Patented Dec. 7, 1915.

Application filed October 2, 1915. Serial No. 53,852. Term of patent 3½ years.

To all whom it may concern:

Be it known that I, PHILLIP EBELING, a citizen of the United States, and residing at Moundsville, in the county of Marshall and State of West Virginia, have invented a certain new, original, and ornamental Design for a Glass Dish or Similar Article, of which the following is a specification, reference being had to the drawings, forming a part thereof, in which—

Figure 1 is a side elevation of the dish,

and Fig. 2 a view thereof partly in top plan and partly in sectional plan, the plane of the portion in section being indicated by line 2—2 of Fig. 1.

I claim:

The ornamental design for a glass dish or similar article, substantially as shown.

PHILLIP EBELING.
